CARD HOLDER AND DISPLAY STAND

Elliott S. Yancey, Houston, Tex.

Application May 15, 1933, Serial No. 671,162

12 Claims. (Cl. 40—10)

The invention relates to an improved display card holder of the type used in stores in merchandising goods.

In the present day methods of merchandising goods it is desirable to place a price tag near each item of merchandise so that the purchaser may be advised as to the price thereof. In order to position the price tag or display card adjacent the articles to which it relates it is often desirable to attach the card directly to the article of merchandise. In order to accomplish this the present type of holder has been devised.

It is one of the objects of the invention to provide a card holder to which the card may be securely locked or latched so that it will not be inadvertently removed.

Another object of the invention is to position the card on the holder in proper relationship so that it will be held firmly in place.

Another object of the invention is to provide, in combination with a card holder, different types of latching mechanisms to hold the card in position.

It is also one of the objects of the invention to provide various types of bases so that the holder may be placed adjacent various types of merchandise.

The foregoing and other objects of the invention will be readily apparent when the following description is considered in connection with the accompanying drawings wherein

Fig. 1 is a back side view of one form of the holder, the view being taken on the line 1—1 of Fig. 2.

Fig. 2 is a side elevation of a holder wherein an article of merchandise rests on the base of the holder to retain it in proper position with an attachment for the article so that the holder will not be displaced.

Fig. 3 shows a second form of the invention embodying a type of base to be used in connection with vegetables or bulk merchandise, and wherein the form of latching mechanism is slightly modified from that shown in Fig. 1.

Fig. 4 is a central vertical sectional view through the latching mechanism of Fig. 3.

Fig. 5 is a section taken on the line 5—5 of Fig. 1 and showing the pin lock.

Fig. 6 is a section taken on the line 6—6 of Fig. 3 and showing the pin lock.

Figs. 7 and 8 are a back view and side elevation, respectively, of a third form of the invention where the base is adapted for insertion in bulk goods and wherein a third form of pin locking mechanism is provided.

Fig. 9 shows a fourth modification of the invention which is somewhat similar to the form of Fig. 1, but which is adapted to be inverted so that the card will be displayed at an elevation below the article of merchandise.

Fig. 10 is a side elevation of the suspended form of the invention shown in Fig. 9.

Figs. 11 and 12 are a side view and a front view, respectively, of the form of clip which may be used in connection with any of the modifications of the invention, which clip is arranged to engage either a thin or a thick card.

Fig. 13 is a vertical sectional view of the form of pin locking mechanism shown in Figs. 7 and 8.

One form of the holder is best seen in Figs. 1 and 2 and includes the holder 1 which is made up of a base 2 and a body portion 3. In this form of the invention the base 2 is shown as having been bent at an angle with respect to the body 3 in order that an article of merchandise such as a can of goods 4 may be positioned on the base, so that the weight thereof will tend to retain the holder 1 in proper position. It seems obvious that the base 2 can be inserted under the can 4 and merely the weight of the can will serve to hold it in position. This type of holder is of particular advantage in grocery stores of self-serve type where it is necessary to frequently change the price and to have the price displayed closely adjacent the particular article.

In some cases where the cans are stacked in special piles on the floor, or otherwise, it is desirable to have a holder securely fastened in position. With this in mind a rubber band or similar attaching means 5 may be provided. This band 5 is shown as having been passed around the can 4 and beneath the finger 6, which is shown as having been stamped from the body 3 of the holder. This finger 6 is seen in rear elevation in Fig. 1 and in side elevation in Fig. 2. When the band 5 has been passed beneath the finger 6 and around the can, the can is then held securely to the holder and the holder will not become misplaced.

In order that the card to be displayed may be securely attached to the holder two spaced clips 8 are shown as having been offset from the plane of the body 3 so that they may serve as a support for the card. These clips may be formed as shown in Figs. 1 and 2, or they may be formed as shown in Figs. 11 and 12, so that they will be adapted to receive either a thin or a thick card. In either instance these clips are offset toward the front of the body 3 so that a card such as 10 when placed against the body 3 can be moved down.

wardly and received by the clip. In some instances the springlike action of the clip 8 may serve to hold the card in position. It is contemplated, however, that the card will be locked in position by a suitable pin lock, one form of which is shown in Figs. 1 and 2.

The pin lock includes an opening 12, which is made in the body 3 at an elevation such that the card will be held in engagement with the clips 8.

- 10 A pin or latch member which has a stem 13 is used to hold the card in position and may be inserted as follows: The card 10 may take any desired shape or configuration and will be moved into position behind the clips 8, as seen in Figs. 1 and 2. The point 14 of the pin will then be moved from the rear of the body 3 through the opening so as to make a hole, such as 15, in the card 10. This hole is formed while the card is firmly held against the holder 3 and as soon as 20 the hole is made the point 14 of the pin is removed. The pin is then passed through the card from the front, passing through the hole 15 and the opening 12 until the head 16 thereof is drawn tightly against the front of the card and against 25 the hole 15.

It is to be understood that the pin has its stem 13 bent at a right angle, as shown in Figs. 1 and 2, either previous to its insertion, or it may be bent after the pin has drawn the card and the 30 holder together. In either event the head 16 is drawn tightly against the card and the pin moved to a position substantially parallel with the body 3 of the holder as seen in Figs. 1 and 2. It is, of course, desirable to lock or latch this pin in 35 position and with this in mind a spring detent 20 is shown as having been stamped from the body 3. This detent is offset from the body so that the point 14 of the pin may be passed laterally beneath the detent. If desired the detent may be 40 grooved as at 21 so that the pin will be accurately positioned and held against displacement. Of course, when the pin is moved into this position the head 16 is drawn tightly against the card and it has been found in practice that this latching 45 mechanism serves to securely lock or latch the card in position. If desired, the body 3 may be stamped with reenforcing ribs 22. It is intended that the holder may be formed of any suitable material.

50 Fig. 3 shows a second form of the invention where the base 25 has been formed in the shape of a tapered point which may be beveled as at 26 in order that it may be inserted into bulk goods. This form is suitable for vegetable stands and any 55 type of goods where the holder is to be supported by contact with the materials.

The body of this modification of the invention is the same as that described in connection with Fig. 1 and it is, therefore, indicated by the same 60 reference numeral 3. The clips 8 are the same as previously described and the general form of latching mechanism is also similar to the Fig. 1 modification. In addition, however, a depression or lug 28 has been shown directly below the 65 opening 12 so that when the pin 13 is moved down to latching position it will bear against this lug and the head 16 will be drawn more firmly against the card 10. This arrangement is shown in detail in Fig. 4. The form of latch shown in Fig. 1 has 70 been modified somewhat and the detent 29 is shown as having been stamped from the body 3 in such a manner that it extends laterally from the body and is provided with a recess 30 to receive the pin.

75 In Figs. 7 and 8 is shown a third form of the

invention wherein the base of the holder is provided with a pair of spaced legs 40. This form of base is particularly adapted for use on vegetable stands and is formed preferably integral with the body 3, which is the same as in the Figs. 1 and 3 modifications. The clips 8 are the same as those previously described.

5 The latching mechanism or pin lock is somewhat different in this form of the invention and is seen in detail in Fig. 13. In this form of the 10 lock a pin stem 41 has been provided which is bent in a loop, as at 42, and includes the straight portion 43 and the point 44. The body 3 is cut away as at 45 and a bearing clip 46 is shown as having been fastened to the body 3 by means of 15 the bent over ends 47.

This bearing clip 46 is provided with a recess 49 which receives the bearing pin or cross bar 50. This pin is preferably firmly attached to the pin 41 in the loop 42, as best seen in Fig. 13. This pin 20 is, of course, permanently attached in the form of the invention shown. The bearing clip 46 is cut away as at 48 to permit pivoting of the pin stem 41 in order to latch the pin in position.

With the parts in the position shown in Fig. 13 25 the card 13 will be passed into the clips 8 and the upper part of the card moved against the front face of the body 3. In this movement the point 44 of the pin will be caused to penetrate the card until the card moves up to the elbow 51 of the pin. 30 With the parts in this position the end 52 of the pin will be moved upwardly to the dotted line position and pass beneath the retaining clip 53. When the pin is thus pivoted about the cross bar 50 the point 44 will be moved down to the dotted line position of Fig. 13, so that the card will be placed firmly into position behind the clips 8 and is locked in position because the straight portion 35 43 passes directly through the card. When thus positioned the card can not be moved upwardly 40 without tearing the card or displacing the pin 41. While this form of the invention is slightly more complicated than that of the previous forms the pin is formed as a permanent part of the holder and will always be present for use. To remove 45 the card it is merely necessary to unlatch the pin from the retaining clip 53 and this releases the point 44 from locking engagement with the card.

Figs. 11 and 12 show a form of spring clip 50 wherein the clip is provided with a bent portion 55 by slitting the material below the flat portion 56 of the clip. The clip at the time it is formed is bent so that it would normally assume the dotted line position of Fig. 11. In this manner it is capable of receiving either a thin or a thick 55 card such as 10.

Figs. 9 and 10 show a still further modification 60 which is quite similar to the Fig. 1 form of the invention as relates to the base thereof. The base is indicated at 60 and is bent at a right angle to the body portion 61. The body is somewhat different from the body previously described in connection with the other modification and extends downwardly from the base 60 and is formed with two spaced arms 62. The lower end 65 of each arm is bent reversely to form a clip 63 which serves the same purpose as the clip 8, viz., to support the card 10. In this form of the invention the card will be inserted in the clip 63 and a pin lock of suitable type provided.

70 Figs. 9 and 10 show a retaining latch or clip 65 which is similar to the detent 20 of Fig. 1 in that it has been bent from the material of the body. In this form the detent has been bent back upon the body in order to provide a retainer 75

for the pin 13 which is inserted through an opening 66 which is equivalent of the opening 12 of Fig. 1 of the invention. This modification of the invention is particularly adapted for goods which are deposited upon a shelf so that the base 60 may be passed beneath the articles and on top of the shelf. This allows the card to be displayed at an elevation below the goods so that the goods themselves will also be displayed. There are other 10 suitable locations for this type of holder.

While several forms of the invention have been shown and described it is to be understood that in view of the large number of uses to which the holder may be applied any desired holder may be 15 made up, using any one of the bases shown or any one of the pin locks described.

What I claim is:

1. A display card holder comprising a backing for the card, an opening therein, a support for 20 the card, a card disposed on said support, means including a pin lock passing through said card and said opening, and bent over to prevent removal, and anchor means to receive said pin lock to retain said card on said holder.

2. A card holder for merchandising articles including means to support a card, a backing for the card, and attaching means passing through the card and backing to retain it fixed on said holder, said means being latched to said backing.

3. A card holder including means to support a card, a backing for the card, attaching means passing thru the card and said backing whereby the card is fixed on said holder, and means on 30 said backing to latch said attaching means to said backing.

4. A holder of the character described including a body, a pair of spaced card supporting lugs thereon, a card lock comprising a pin passing thru a card and said body and bent to a position 40 along said body, and means on said body to receive said pin whereby the card is locked in position.

5. In combination with a card holder, a lock to retain a card in fixed position on the holder comprising a pin passed thru the card and the card holder with the pin head drawn down against the card, and means to receive said pin to latch it in locking position.

6. A card holder including a base by which said holder is supported, a body portion carried by said base, clips thereon to receive a card, and locking means passing through said body and the card to hold the card in fixed position on said body. 5

7. A card holder including a base by which said holder is supported, a body portion, clips thereon to receive a card, and locking means passing through said body and the card to hold 10 the card in fixed position on said body, said clips being spring like to receive different thicknesses of cards.

8. A card holder including a base by which said holder is supported, a body portion, clips thereon to receive a card, and locking means to hold the card in fixed position on said body, said locking means including a bent pin having a head, and a detent to receive said pin.

9. A card holder including a base by which 20 said holder is supported, a body portion, clips thereon to receive a card, and locking means to hold the card in fixed position on said body, said locking means including a pin pivoted on said body and having a point to pierce the card. 25

10. A locking device for card holders including a bearing clip, a body to which said clip is engaged, a bearing pin in said clip, a locking pin passing thru said clip and body and having a point projecting from the body to pierce a card 30 when it is positioned, and means to engage the opposite end of said pin whereby the card is held in fixed position.

11. In a pin lock for display card holders, a pin having a head, a body adapted to receive said 35 pin, a lug on said body, and a pin latch also on said body whereby said pin when passed thru a card and the body will have its head drawn against the card when the stem of the pin is moved against said lug and received by said latch. 40

12. A card holder including a base adapted to receive an article of merchandise, means on the holder to receive and lock a card to the holder, and means including a rubber band passed about the article and connected to the holder whereby 45 said holder is held in position by the article received on the base.

ELLIOTT S. YANCEY.
